(57) **CLAIM**

The ornamental design for a shoe box, as shown and described.

DESCRIPTION

FIG. 1 is a front and top perspective view of a first embodiment of a shoe box, showing my new design;
FIG. 2 is a rear and top perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is an enlarged perspective view of detail "9" identified in FIG. 1;
FIG. 10 is an enlarged perspective view of detail "10" identified in FIG. 1;
FIG. 11 is an enlarged perspective view of detail "11" identified in FIG. 2;
FIG. 12 is a front and top perspective view of a second embodiment of the shoe box;
FIG. 13 is a rear and top perspective view thereof;
FIG. 14 is a front view thereof;
FIG. 15 is a rear view thereof;
FIG. 16 is a left side view thereof;
FIG. 17 is a right side view thereof;
FIG. 18 is a top view thereof;
FIG. 19 is a bottom view thereof;
FIG. 20 is an enlarged perspective view of detail "20" identified in FIG. 12;
FIG. 21 is an enlarged perspective view of detail "21" identified in FIG. 12; and,
FIG. 22 is an enlarged perspective view of detail "22" identified in FIG. 13.

The dashed lines in the figures illustrate portions of the shoe box that form no part of the claimed design. The dash dot dash lines in FIGS. 1, 2, 9, 10, 11, 12, 13, 20, 21 and 22 are for the purpose of illustrating the enlarged views indicators and form no part of the claimed design.
